UNITED STATES PATENT OFFICE.

JAMES HALL TAYLOR, OF OAK PARK, ILLINOIS.

RING-ROLLING MACHINE.

Application filed November 28, 1924. Serial No. 752,525.

This invention relates to a ring rolling machine or mill of the type in which a ring is reduced and put in finished form.

It is among the objects of this invention to eliminate as far as possible the slippage of the rolls that more or less roughens the surfaces of the rolled ring and the objectionable cross cutting of the ring that frequently occurs.

With these and other objects in view which will become more apparent in the following description and disclosures in the drawings, this invention comprises the novel structure and combinations hereinafter described and more particularly pointed out and defined in the appended claims.

In the accompanying drawings which illustrate a preferred embodiment of this invention and in which similar reference numerals refer to similar features in the different views:

20 Figure 1 is a longitudinal sectional view through the ring rolling machine.

Figure 2 is an enlarged sectional view through the differential drive for certain rolls.

25 Figure 3 is an enlarged horizontal sectional view of the machine substantially upon the line 3—3 of Figure 1.

Figure 4 is an enlarged sectional view through the lower roll and the bearing therefor.

30 Figure 5 is an enlarged front elevational view of the machine.

Figure 6 is a fragmentary side elevational view of a slightly modified form of machine or mill.

35 Figure 7 is a front elevational view of the modified form of machine.

As shown on the drawings:

In referring to the drawings there is shown a stationary frame 1 having a vertical bearing 2 and a depending bearing lug 3. A sleeve 4 is rotatably mounted in the vertical bearing 2 and a bevelled pinion 5 is keyed upon the lower end of the sleeve 5 which projects below the bearing 2 for this purpose. A shaft 6 is slidably splined in the bearing sleeve 4. The upper end 6^a of this shaft constitutes a roller for engaging the inner periphery of the ring. An inclined roller bearing ring 7 is secured to the upper portion of the bearing 2 and to the upper end 6^a of the shaft 6. The lower end 6^b of the shaft 6 rests upon a block 1^a secured to the frame 1 adjacent said bearing 2 and a roll 8 having a roller race in its lower surface surrounds the roller ring 7, suitable conical anti-friction rollers 9 being interposed between the bearing 2 and roll 8. The roll 8 has an inclined flange

8^a to which a plate 10 is secured, the flange and plate define a V which slidably fits over the bearing ring 7 which has a V shaped periphery for this purpose. The roll 8 is provided with a rolling surface 8^b that is adapted for engaging one side of the ring which in the drawings is shown as being the lower side, and at right angles to the rolling face 8^b there is a second rolling face 8^c that engages the roll portion 6^a of the shaft 6. The side of the roll that contains the rolling surface 8^c projects beyond the portion containing the roller bearing race whereby a form of rabbet 11 is formed to allow clearance for the upper end of the sleeve 4. Dust proof means 13 may be positioned between the adjacent faces of the roller races and a loose brass ring 12 or the like may be placed between the bearing 7 and plate 10 to provide a good bearing surface. The roll 8 may be provided with cooling ducts 14 through which matter may also escape from the rabbet 11 and the bearing 2 may likewise be made with a duct 15 for a similar purpose. In referring to Figure 1 it will be noted that the stationary bearing ring 7 is supported upon the block 1^a just below the point where the roller 8 engages the ring 16 that is being rolled so that the downward thrust is absorbed by the frame 1 that supports the block 1^a. It is apparent that the roll 8 is freely floating, that is, it is not positively driven except through the friction engendered between it and the rolled ring 16 as will later more fully appear. The inclination of the roll 8 is preferably at an angle of 45° to the axis of the bearing.

The frame 1 has a laterally projecting flange or rail 17 (Figure 5) upon each side upon which a carriage is mounted for longitudinal adjustment. This longitudinally adjustable carriage comprises a pair of parallel depending wings or members 18 provided with mortises or guide grooves 19 for receiving the rails 17. A transverse member 20 extends between the wings 18 for rotatably supporting a shaft 21 provided with an upper collar 22 which rests upon the member 20 and a lower collar 23 which bears against the bottom of the member 20 whereby the shaft is rotatably anchored against vertical movement. A worm gear 24 is secured upon the upper end of the shaft 21. This worm gear is driven by a small worm 25 on the shaft of a motor 26 supported on the longitudinally movable carriage. The lower end of the shaft

21 is threaded into a lug 27 on a vertically slidable bearing 28 maintained in the guide grooves 29 (Figure 3) of the wings 18. The bearing 28 is provided with an inclined journal bearing in which a shaft or journal 30 is mounted. The shaft 30 has a frusto-conical roll 31 secured upon its lower end. This roll is adapted for engaging and rolling one side of the ring 16. In the drawing, the 10 roll 31 is shown as engaging the upper side of the ring. The other or upper end of the shaft 30 carries a bevelled gear 32 that is driven by a similar gear 33 supported upon a shaft 34 journalled in a bearing 35 on an 15 arm 36 extending from the bearing 28. The shaft 34 is adapted to be coupled to the shaft of a driving means which is preferably an A. C. motor.

Upon the lug 27 of the bearing 28 there is 20 secured a transverse member 37 provided with trunnions 38 at its ends. A bar 39 is adjustably mounted upon the lower end of the aforementioned shaft 6 which is threaded at its lower end for the application of the nuts 25 which engage the bar 39 and retain the same in adjusted position. The ends of the bar 39 are provided with trunnions 38. Links 41 pivotally connect the corresponding trunnions of the bars 37 and 39. According to 30 this construction the upper end of the shaft 6 may be readily maintained in contacting relation with the roll 31 if desirable since the bar 39 is susceptible of vertical adjustment on the shaft 6. The shaft 6 also partakes of the adjustment of the bearing 28 35 so that this contacting relation may be maintained when the bearing 28 is vertically adjusted.

The aforementioned carriage also has a 40 bearing member 42 which has a depending bearing lug 43 slidably embracing a drive shaft 44 which is rotatably supported thereby and also by the aforementioned bearing lug 3 and a bearing lug 45 depending from 45 the stationary frame 1. A bevelled gear 46 upon the inner end of the shaft 44 meshes with the gear 5 on the rotatable sleeve 4 for imparting rotation thereto. The shaft 44 is driven by means of a bevelled gear 47 which 50 in turn is driven by a bevelled gear 48 which is differentially driven by a differential drive that will presently be described.

The bearing member 42 has also a pair of parallel horizontal bearing lugs 49 and 50 55 in which the ends of a hollow sleeve or spider 51 are journalled as shown in Figure 2. This spider has a bevelled gear 52 secured thereon. This spider also carries interiorly thereof the usual differential pinions 53 rotatably mounted upon short stub shafts 54 carried by the spider. Within the ends of the spider are journalled a pair of bearing sleeves 55 which terminate at their adjacent faces in bevelled gears 56 which are in mesh with the 60 differential pinions 53. A shaft 57 is se-

cured in one of the sleeves 55 and the same carries the differential gear 48. A shaft 58 is secured in the other sleeve 55 and carries a spur gear 59 upon its outer end. The inner portions of the shafts 57 and 58 and the interior of the sleeves 55 are preferably of polygonal form for securing conjoint rotation between each shaft and its sleeve. 70

The gear 59 meshes with a pair of gears 60 (Figure 3) upon shafts 61 supported at 75 their ends in the bearing member 42, which has a forwardly extending portion for this purpose, and a plate 62 above such extended portion. A friction drum 63 is associated with each gear 60 for frictionally driving a 80 roll 64 which is supported upon a shaft 65 mounted in the forward ends of the plate 62 and the bearing 42. The drums are designed to contact said roll 64 upon points approximately 90 degrees apart measured upon the 85 periphery of said roll. The roll 64 is adapted to engage the outer periphery of the ring to be rolled.

In referring to Figure 1 it will be noted that the frusto-conical roll 31 overlaps the 90 end of the roll 6^a and that the freely floating roll 8 contacts the roll 6^a at the ring pass and overlaps the roll 64 which in turn overlaps the rear of the conical roll 31 which is provided with a bevelled rear edge 31^a for this 95 purpose, consequently a closed pass is formed through which the ring passes as it is reduced and rolled into finished form.

The gear 52 of the differential is driven by a small bevelled pinion 66 upon a shaft 66 journalled in a depending lug 67 on the carriage and in a bearing formed in the stationary frame 1. This shaft 66 is preferably driven by an A. C. motor. The differential gearing drives the inner peripheral roll 6^a and the outer peripheral roll 64. Consequently these rolls may rotate at various speeds and one may rotate slower than the other to eliminate slippage with respect to the ring that is being rolled. It is well known that such slippage of the rolls frequently produces striations or a rough surface on the ring and it is highly desirable to eliminate the same. As the lower roll 8 is not positively driven but is carried around by its frictional engagement with the ring, there will be no slippage between the upper and lower rolls. 110 115

In referring to Figures 6 and 7 which illustrate modified features it will be noted that the cross bar 37 that is attached to the movable bearing 28 pivotally supports a pair of links 68 which are provided with sockets 69 at their lower ends which engage over the spherical heads 70 upon adjustable screws 71 slidably splined in a cross head 72 having a 120 plunger 73 centrally of its lower surface which operates in a fluid pressure cylinder 74. In order to simultaneously adjust the screws 71 a hand wheel 76 is threaded upon each screw above the cross head. The hub 125 130

of each hand wheel has an integral sprocket wheel 77 and a sprocket chain 78 is trained over said sprocket wheels. The operation of one of the hand wheels will simultaneously 5 rotate the other in the same direction, consequently the screws may be raised or lowered thereby. Centrally of the cross head 72 there is a bearing socket 78 into which the lower end 10 of the shaft 79 extends that terminates in the upper inner peripheral roll 6^a. According to this construction the cross head 72 may be lowered thereby lowering the roll 6^a to provide sufficient space for the insertion or 15 removal of the ring 16 making it unnecessary in most cases to shift the carriage or upper bearing and the adjustment of the links 68 through the screws 71 serves to maintain the rolls 6^a and 31 in proper relation.

The ring 16 that is being rolled is supported 20 in the ring pass defined by the aforementioned rolls and a movable ring support 80 provided with oppositely directed rolls 81 for engaging the opposite corners of the ring. When it is desired to insert a ring between the rolls or 25 remove one, the carriage is moved to right as viewed in Figure 1, there being sufficient lost motion with respect to the links 41 for this purpose, while in the structure shown in Figure 7 the links 68 can be adjusted.

30 It is well known that as the ring is rolled and reduced the inner and outer peripheries are varied, so that it is impossible to design peripheral rolls that will always have a true rolling action, consequently there will be 35 slippage at times. However by introducing the differential drive this slippage of the inner and outer peripheral rolls is eliminated. It will also be appreciated that the inclination of the roll 8 will produce substantially 40 only a line contact with the ring and as it rotates in the direction of the travel of the ring there will be no cross cutting of the ring. Further the freely floating character of the ring prevents relative slippage with respect 45 to the conical roll. In practice it has been found that rings rolled in this machine have excellent smooth surfaces free of striations or cross cutting.

I am aware that many changes may be 50 made, and numerous details of construction may be varied through a wide range without departing from the principles of this invention, and I therefore do not purpose limiting the patent granted hereon, otherwise than 55 necessitated by the prior art.

I claim as my invention:

1. In a ring rolling machine, a frusto-conical roll for engaging one side of the ring, a roll for engaging the inner periphery of the 60 ring, a roll having its axis inclined with respect to the last mentioned roll for engaging the other side of the ring, a roll for engaging the outer periphery of the ring, said rolls defining a closed pass.

65 2. In a ring rolling machine, a roll for en-

gaging one side of the ring, a roll for engaging the exterior periphery of the ring, a roll for engaging the opposite side of the ring and a roll passing through said last mentioned roll at an angle to the axis of said last mentioned roll for engaging the interior periphery of the ring. 70

3. In a ring rolling mill, a bearing, a roll 75 slidably supported in said bearing, a roll supported for rotation around said bearing and having its axis inclined with respect to the axis of the first roll, and means cooperating with said rolls for defining a ring pass.

4. In a ring rolling machine, a pair of rolls having axially adjustable telescopic relation 80 and having their axes intersecting at an angle.

5. In a ring rolling mill, a cylindrical bearing, a roll rotatable about said bearing with its axis at an angle to the axis of said bearing, a second roll slidably supported in said bearing, and means cooperating with said rolls for defining a ring pass. 85

6. In a ring rolling machine, a frusto-conical roll for engaging one side of the ring, a roll for engaging the outer periphery of said ring, a cylindrical bearing, a roll 90 slidably mounted in said bearing for engaging the interior periphery of said ring, and a roll mounted for rotation about said bearing at an inclined angle to the axis of said bearing for rolling the other side of said ring. 95

7. In a ring rolling machine, a frusto-conical roll for rolling one side of the ring, a freely floating roll engaging the other side of the ring and rolls for rolling the peripheries of the ring, said rolls defining a closed pass. 100

8. In a ring rolling machine, a roll for engaging one side of the ring, an inclined and 105 freely floating roll for engaging the other side of the ring and rolls for engaging the inner and outer peripheries of the ring.

9. In a ring rolling machine, a frusto-conical roll for engaging one side of the ring, an inclined and freely floating roll for engaging the other side of the ring, a shaft 110 extending through said freely floating roll and embodying a rolling surface for engaging the inner periphery of the ring and a roll for engaging the outer periphery of said ring. 115

10. In a ring rolling machine, the combination with a pair of rolls for engaging the sides of the ring, one of said rolls being positively driven and the other being freely rotatable, a pair of rolls for engaging the inner and outer peripheries of said ring, and a differential driving mechanism for said last mentioned rolls. 120

11. In a ring rolling machine, the combination with a pair of rolls for rolling the sides of the ring, one of said rolls comprising an inclined freely floating member, and a pair of differentially driven rolls for engaging the inner and outer peripheries of said ring. 125 130

12. In a ring rolling machine, a frusto-conical roll for engaging one side of the ring, a roll for engaging the interior periphery of said ring, a roll surrounding said last mentioned roll at an inclined angle to the axis thereof, a roll for engaging the exterior periphery of said ring, and a differential drive for said second and last mentioned rolls.
13. In a ring rolling mill, a pair of rolls for respectively rolling the sides of said ring, one of said rolls being freely floated, and a pair of differentially driven rolls for respectively engaging the inner and outer peripheries of said ring, said rolls defining a closed pass.
14. In a ring rolling mill, a pair of rolls, one extending through the other, the axis of said rolls being at an angle to each other and means co-operating with said rolls for forming a ring pass.
15. In a ring rolling mill, a pair of rolls, one having a supporting track around the axis of the other at an inclined angle thereto in combination with mechanism for forming a ring pass.
16. In a ring rolling mill, the combination with a plurality of rolls defining a closed ring pass, one of said rolls being axially shiftable for access to said pass.
17. In a ring rolling mill, a roll, an adjustable bearing therefor, a bar secured to said bearing, links pivoted at their upper ends to said bar, said links having bearing sockets at their lower ends, a cross head, fluid pressure means acting on said cross head, a roll shaft supported on said cross head, and adjustable elements on said cross head fitting in the sockets of said links.
18. In a ring rolling mill, the combination with a plurality of rolls defining a closed ring pass, an adjustable support for one roll, a fluid actuated support for another roll and pivotal and adjustable means connecting said supports.
19. In a ring rolling mill, the combination with a plurality of rolls defining a ring pass, one of said rolls extending through another roll at an angle of substantially 45°.
20. In a ring rolling mill, a roll having a shaft shiftable in an axial direction and a roll mounted for rotation about said shaft at an inclined angle thereto.
21. In a ring rolling machine, the combination with a support, of a roll carried thereby, a movable support, a roll axially supported thereon, said movable support being controlled in one direction of movement by said first mentioned support.
22. In a ring rolling machine, a support, a roll supported thereby, a movable carriage, a cooperating roll carried thereby, and an adjustable connection between said carriage and first mentioned roll.
23. In a ring rolling machine, a support, a roll mounted therein for axial shifting movements, a support for said roll, a movable carriage, a cooperating roll carried by said carriage, and adjustable means connecting said carriage and second mentioned support.
24. In a ring rolling machine, a roll for acting on the outer periphery of the ring, a roll for acting upon the inner periphery of the ring, an inclined freely floating roll surrounding one of said first mentioned rolls for acting on a side of the ring and a differential driving mechanism for rotating said first mentioned rolls.
25. In a ring rolling mill, a movable roll, a shiftable carriage, a support for said roll, a pair of rods connecting said support and carriage and simultaneously operated means for adjusting said rods.
26. In a ring rolling mill, a roll for acting on the inner periphery of said ring, a roll for acting on the outer periphery of said ring and a freely floating roll engaging one side of the ring.

In testimony whereof I have hereunto subscribed my name.

JAMES HALL TAYLOR.
